UNITED STATES PATENT OFFICE.

SIDNEY C. HILLS, OF TORRINGTON, CONNECTICUT, ASSIGNOR TO THE TURNER & SEYMOUR MANUFACTURING CO., OF TORRINGTON, CONNECTICUT, A CORPORATION.

CURTAIN-ROD.

1,214,678.

Specification of Letters Patent.

Patented Feb. 6, 1917.

Application filed November 16, 1914. Serial No. 872,341.

To all whom it may concern:

Be it known that I, SIDNEY C. HILLS, a citizen of the United States, and a resident of Torrington, county of Litchfield, State 5 of Connecticut, have invented a certain new and useful Improvement in Curtain-Rods, of which the following is a specification.

My invention relates to curtain rods more particularly of the type adapted to support 10 light weight curtains, draperies and the like and has for its object to construct and support the rod so that the curtain or other drapery may be draped thereon in a novel and graceful manner and so as at all times 15 completely to conceal the brackets or other supporting means as well as the rod itself from view, thus doing away with the ornamental and oftentimes unsightly exposure of these parts which with ordinary 20 constructions it is difficult to avoid.

A further object of my improvement is to preserve at all times a harmonious relation between the curtain and the opening over which it is draped and to prevent the 25 usual creeping of the curtain or the like which takes place with rods as ordinarily constructed and exposes a section of the window intended to be covered and in consequence frequently admits an objectionable 30 streak of light into the room.

In the early development of the art to which the present invention relates cornices were first utilized to cover the support from which the curtains were suspended, such 35 cornices usually being heavy and awkward and often out of harmony with their surroundings. The next step in the art resulted in the employment of simple straight metal or other rods which presented the 40 advantage of objectionably limiting the arrangement of the curtains thereon and which in most cases prevented the curtains from being gracefully draped and also exposed to view the supports on which the rods 45 were mounted together with a large part of the rods themselves. Following the use of the straight rods as above mentioned came rods having their opposite ends bent at substantially right angles to the main portions 50 of the rods and directly secured to the casing surrounding the opening over which the curtains were draped. With this latter construction, it usually became necessary, owing to the presence of moldings and the like,

to secure said end portions at a distance 55 inside of the outer edges of the casing. With such arrangement, if the curtains were looped back at their lower portions an objectionable inclined line was formed at the outer edges of the curtains extending from 60 the outer end portions of the rods to the points at which the curtains were looped back, this point being usually somewhere along the outer edges of the said casing. This resulted in an uneven and unornamental 65 exposure of said casing when viewed from the front and absolutely destroyed the symmetry and harmony of the hanging. My improvement in all of its forms overcomes such objectionable features. 70

My invention will be fully described hereinafter and the features of novelty will be pointed out in the appended claims.

Reference is to be had to the accompanying drawings which illustrate examples of 75 my invention and in which—

Figure 1 is a plan view of the rod as attached for instance to a window and with the curtain shown in dotted lines draped thereon; Fig. 2 is a front elevation showing 80 the curtain as it appears when draped in my novel manner. Fig. 3 is a side elevation thereof; Fig. 4 is a plan view partly in section of another form of rod; Fig. 5 is a detail plan view partly in section illustrating 85 a novel form of supporting bracket; Fig. 6 is a detail front view thereof; Fig. 7 is a detail cross-section on the line 7—7 of Fig. 5; and Fig. 8 is a similar view of another form of said bracket. 90

As shown in Figs. 1, 2, and 3 the curtain rod comprises two main sections 1 and 2 arranged to telescope one within the other for the purposes of adjustment and having their free ends extended or bent rearward and 95 inward toward each other, for instance, in the form of a semicircle as indicated at 3 and 4. Any suitable means may be utilized for supporting the rod in position over a window, door or the like, the illustration 100 showing hooks or brackets 5 secured to the window or other frame 6 and adapted to extend into apertures 7 with which the sections 1 and 2 are provided at points closely adjacent to their inwardly extending free ends. In this manner the main portion of the curtain rod is supported at a distance 105 in front of the window or the like while the

ends thereof curve or otherwise project toward and are in close proximity to the frame of said window or the like as shown in Fig. 1. With this arrangement the hooks 5 or brackets 5 are located at points within the outside limits of the rod, it being understood that springs 8 or similar devices may be used in combination with the brackets 5 to prevent unintentional dislocation of the 10 rod, while the outermost portions of said rod are substantially in line with the outer edges of the window, door or other casing. The curtains 9 are draped upon the sections 1 and 2 before the same are combined and 15 placed in position on the brackets and are then carried completely around the curved ends of said sections into close proximity to the brackets 5. In this manner the curtains 9 at their opposite outer portions hang 20 gracefully in a full roll or loose fold extending downwardly, substantially in line with the outer edges of the window, door or other casing and which is extremely ornamental and pleasing to the eye and at the same time 25 serves to completely conceal the brackets 5. In addition, this arrangement of the curtains on rods constructed in the manner described prevents the curtains from creeping sufficiently to expose the door, window or 30 other casing or the window or door opening, the said creeping being reduced to a minimum and at most extending over only a small portion of the rods at the inwardly extending end portions 3 and 4 thereof. 35 The described draping of the curtains at all times preserves a harmonious relation between the curtains and the casing and also permits the said curtains to be more gracefully disposed than when hung from curtain 40 rods as ordinarily constructed, the arrangement from every point of view presenting a soft, ornamental appearance to the eye without any discordant or harsh lines or effects. 45 As shown in Fig. 4 the rod itself comprises two straight sections 1^a and 2^a telescopically engaged with each other and arranged to have their ends extend over brackets 5^a secured to a frame 6 and having their 50 ends extend toward each other. These brackets extend forwardly and inwardly for instance in the form of semi-circles or are otherwise shaped with their free ends projecting toward each other and substantially 55 form continuations of the rod sections 1^a and 2^a when connected therewith, so that when the rod is in operative position on said brackets the combined structure forms a curtain rod having substantially the same characteristics and advantages as the one illustrated in Fig. 1. The curtain or other drapery may be draped upon the form of my invention in the same way as in the form 60 first described and when so arranged presents the same appearance and advantages.

The ends of the rod sections 1^a and 2^a may frictionally engage said brackets 5^a to prevent accidental disengagement of the rod and brackets or coöperating recesses and projections 5^b may be provided on the rod 70 and brackets respectively to guard against such a contingency.

The bracket shown in Figs. 5, 6 and 7 comprises a member 10 having its opposite edges curved or otherwise shaped to form hooks 75 or similar flanges 11 and provided on its rear surface with a projecting screw or other fastening device 12 whereby said brackets may be secured to a window casing or the like. The rod 1^b in this case has its free 80 ends split for a distance as shown at 12 and shaped to form beads or the like 13 corresponding in shape and adapted to fit within the hooks or flanges 11. The rod 1^b is attached to the bracket by simply inserting 85 an end of said rod into an end of the bracket and is maintained in position therein through the frictional engagement of the beads or the like 13 with the hooks or flanges 11 and by means of the elasticity of 90 the rod material at its free end or by recesses and projections engaging one with the other. The rod 1^b may be curved or otherwise shaped at its end portions in the same manner as in the previous forms of my device 95 and operates and may be utilized in exactly the same way and presents the same advantages.

Instead of forming the bracket as in Fig. 7 the flange 11 may be continued to form a 100 front wall 11^a as shown in Fig. 8, this type of bracket coöperating with the rod 1^b and supporting the same in substantially the same way as does the bracket illustrated in Figs. 5, 6 and 7. The brackets shown in 105 Figs. 7 and 8 are preferably provided with a projecting shoulder 14 or the like whereby said brackets are maintained at a distance from the window or other casing sufficient to permit the curtain 9 to be draped around the ends of the rod as described without coming into too close contact with or being injuriously clamped between the casing and the bracket. Damage to the curtain, when draped in this manner is thus prevented. 110

It will be obvious that the curtain rod instead of being telescopically or otherwise adjustably constructed may be made in the form of a single continuous rod having a fixed length and its ends constructed as described and illustrated. Furthermore, provision may be made for supporting double draperies or a valance in the manner set forth by suitably combining two rods having the characteristics of the improvements described herein. It will further be apparent that the form or shape of the said brackets shown in Figs. 5 and 8 may be otherwise changed from the particular designs shown and that the ends of the rods may be made 115 120 125 130

to conform thereto without departing from the inventive idea included herein.

Various other changes in the specific forms shown and described may be made within 5 the scope of the claims without departing from the spirit of my invention.

I claim:

1. The combination of a curtain rod having a main central portion and being curved 10 rearwardly at its ends to provide end portions extending parallel to and in spaced relation to said main central portion and brackets for engaging said rear portions, and for maintaining said main central portion 15 and end portions in substantially the same horizontal plane whereby the curtains may be draped in depending rolls at said end portions and the inner edges of said curtains, the brackets and curtain rod are substantially concealed.

2. The combination of a pair of brackets each provided with a horizontally disposed 20

recess having an open end, and a curtain rod having its ends curved back toward each other and fitted into the open ends of the 25 recesses of said brackets.

3. The combination of a bracket comprising a main portion and hook like flanges at its opposite horizontal edges forming a horizontally open recess, a fastening device carried by said main portion, a curtain rod having its end bent back upon itself in a wide bend and beads located at the terminating portion of said end and adapted to extend into said recess and fit within said hook like 30 flanges and frictionally engage the same.

In testimony whereof, I have hereunto set my hand in the presence of two subscribing witnesses.

SIDNEY C. HILLS.
